UNITED STATES PATENT OFFICE.

THOMAS HACKERSON, OF NEWARK, ILLINOIS.

FUEL-BOX.

1,223,273.

Specification of Letters Patent. Patented Apr. 17, 1917.

Application filed November 1, 1916. Serial No. 128,916.

To all whom it may concern:

Be it known that I, THOMAS HACKERSON, a citizen of the United States, residing at Newark, in the county of Kendall and State of Illinois, have invented certain new and useful Improvements in Fuel-Boxes; and I do hereby declare the following to be a full, clear, and exact description of the invention, such as will enable others skilled in the art 10 to which it appertains to make and use the same.

This invention relates to a fuel box especially adapted to be used in connection with cooking ranges and has for its primary object the provision of means for storing wood, corn cobs and coal without presenting an unsightly object about the range and which will prevent dirt, dust and the like from escaping within the room in which the device is located when not removing the fuel 20 therefrom.

Another object of this invention is to provide a casing having a bin pivoted therein for containing coal and which is adapted to 25 be swung out of the casing, so that the coal may be removed therefrom for supplying the fire range with fuel.

A further object of this invention is to provide means for supporting the bin when 30 swung outwardly of the casing.

A further object of this invention is to provide a receptacle having the bottom thereof spaced above the lower edges, so as to form a flange adapted to receive a shoulder upon the casing, whereby wood and corn cobs may be stored and the receptacle is capable of being inverted upon the casing and having a door in one wall thereof, so 35 that cooking utensils and the like may be stored within the receptacle and the flange and bottom thereof forming a rack for kindling, when not using wood or corn cobs as a fuel for the fire of the range.

A still further object of this invention is 45 the provision of a fuel box of the above stated character, which shall be simple, durable and efficient, and which may be manufactured and sold at a comparatively low cost.

With these and other objects in view as 50 will become more apparent as the description proceeds, the invention consists in certain novel features of construction, combination and arrangement of parts as will

be hereinafter more fully described and 55 claimed.

For a complete understanding of my invention, reference will be had to the following description and accompanying drawing, in which:

Figure 1 is a perspective view of a fuel box constructed in accordance with my invention, illustrating the bin swung outwardly of the casing,

Fig. 2 is a front elevation of the same, 65

Fig. 3 is a perspective view of the casing with the receptacle removed,

Fig. 4 is a perspective view of the receptacle, and

Fig. 5 is a fragmentary sectional view 70 illustrating the means of pivoting the bin within the casing and the means of supporting the bin when swung outwardly of the casing.

Referring in detail to the drawing, the 75 numeral 1 indicates a substantially rectangular casing having its top wall offset as illustrated at 2 to form a shoulder or flange 3 upon the top of the casing 1. The front wall of the casing 1 is provided with a doorway 4 80 for allowing a bin 5 to be swung outwardly of the casing 1 as clearly illustrated in Fig. 5 in dotted lines and also Fig. 1 in full lines. The bin 5 has its upper end open as clearly 85 illustrated in Fig. 1 and is provided with a curved bottom 6. The bin 5 is pivoted to the side walls of the casing 1 as illustrated at 8 and has secured to the front wall thereof a handle 9' whereby the bin may be swung 90 outwardly of the casing 1. The bin 5 is normally supported vertically within the casing 1 owing to the weight of coal or like fuel within the bin.

A pair of relatively spaced arms 9 have 95 one of their ends connected by a bar 10 and have their free ends pivoted to the side walls of the bin 5 as illustrated at 10'. Each of the arms 9 are slotted as illustrated at 11 and have pins 12 extending therein which are secured to the side walls of the casing 1, 100 whereby when the bin 5 is swung outwardly of the casing 1 through the doorway 4, the arms 9 are swung outwardly from the casing 1 through the doorway 4 so as to support the bin 5, whereby coal or like fuel may 105 be removed from the bin. The bar 10 is adapted to engage the ground or flooring of a building when the bin 5 is swung to an

opened position to prevent the device from tipping over. The bin 5 is divided into two compartments by a partition 13 whereby different characters of fuel may be kept in the 5 bin.

A substantially rectangular receptacle 14 has a bottom 15 secured to the walls thereof at a point above their lower edges so as to provide a flange 16 adapted to fit or receive 10 the shoulder 3 upon the casing 1. The receptacle 14 is employed for containing wood, corn cobs or the like fuel when desiring to feed the fire with such fuel. The end 15 walls of the receptacle 14 have handles 17 secured thereto whereby the receptacle 14 may be removed from the casing 1 and carried to various points when collecting wood or corn cobs therein.

The front wall of the receptacle 14 is provided with a doorway which is normally closed by a door 18 having a catch 19 thereon.

When not desiring to use wood or corn cobs as a fuel for the fire, the receptacle 14 25 may be inverted upon the casing 1 and used as a storing receptacle for cooking utensils or the like by opening the door 18 and placing the cooking utensils or like within the receptacle 14. The flange 16 and the bottom 15 present or form a rack for receiving kindling as clearly illustrated in Fig. 1.

While I have shown and described the preferred embodiment of my invention, it

will be understood that minor changes in construction, combination and arrangement 35 of parts may be made without departing from the spirit and scope of the invention as claimed.

Having thus described my invention what I claim is:

1. A fuel bin comprising a casing having a doorway, a bin pivoted within said casing and adapted to be swung outwardly of the casing through the doorway, a pair of arms pivoted to the casing, means for connecting 45 said arms together, said arms having elongated slots therein, and pins carried by the bin and extending in the slot to cause said arms to move outwardly of the casing with the bin to support the bin. 50

2. A fuel bin comprising a casing having a doorway, a bin pivoted within said casing and having a rounded bottom, a handle secured to said bin for swinging said bin outwardly through the doorway of the casing, 55 and means pivoted within the casing and connected to the bin adapted to swing outwardly of the casing with the bin to support said bin in an open position.

In testimony whereof I affix my signature 60 in presence of two witnesses.

THOMAS HACKERSON.
